UNITED STATES PATENT OFFICE.

HARRY H. CREA, OF DECATUR, ILLINOIS.

FIRELESS COOKER.

No. 875,695.

Specification of Letters Patent.

Patented Jan. 7, 1908.

Application filed, May 3, 1907. Serial No. 371,715.

To all whom it may concern:

Be it known that I, HARRY H. CREA, a citizen of the United States, and resident of Decatur, in the county of Macon and State of Illinois, have invented certain new and useful Improvements in Fireless Cookers, and my preferred manner of carrying out the invention is set forth in the following full, clear and exact description, terminating with 10 claims particularly specifying the novelty.

This invention relates to stoves and furnaces, and more especially to that class of devices thereunder which are employed for cooking; and the object of the same is to 15 produce an improved fireless cooker whose construction will be described below.

The invention comprises but three main parts, to wit: a shell or tub, a nest located centrally within the same and in which nest 20 the pot or kettle is to be placed, and a cover for the nest and shell. The parts are preferably constructed of galvanized iron or other sheet metals which are not susceptible to corrosive action; and certain of them are provided with means for preventing the transmission of heat. Such means I term herein 25 "non-conducting chambers," and I show them as air chambers, although they may contain other non-conducting material in 30 addition to the air. The other point involved in the present invention is that when in use the nest shall be surrounded radially with a plurality of non-conducting chambers and shall be surmounted by a plurality 35 of such chambers, there preferably also being one such chamber beneath it. The object of this construction is to prevent the heat carried by the contained pot or kettle from escaping or radiating to the outside of the device, and the further object is to construct a 40 fireless cooker in such manner that it shall be sanitary because there is ordinarily no packing and hence the parts are readily cleaned when they are separated.

45 Referring to the accompanying drawings— Figure 1 is a plan view of the cooker with the cover removed, Fig. 2 is a bottom plan view of the cover, Fig. 3 is a side elevation of the entire device, showing more particularly the shell, Fig. 4 is a central vertical section through the same, Fig. 5 and 6 are plan views of amplifications of this idea wherein several independent cookers (here shown as 50 without their covers) are contained within one casing.

The shell of this device comprises in the

present illustration a tub consisting of an upright body 1 having suitable handles 2, an open upper end preferably surrounded by a beading 3, and a closed bottom 4. By preference the body 1 is cylindrical as shown, although of course it may be oval, polygonal or of other contour. The handles may be of any proper type or may be omitted entirely. Within the body on the bottom are disposed 60 a number of guides 5 directed from the body obliquely inward toward the center of the shell, and these guides are preferably fixed in place.

The nest for containing the pot or kettle 70 10, preferably comprises a cylindrical body 11 of smaller diameter than that of the shell and resting at its lower edge on the bottom 4, having a central opening or compartment 12 which receives the pot or kettle, a surrounding wall 13 which forms this compartment and is spaced from the body 11 so as to form between them a non-conducting chamber 14, and a flat annular cover 15 for this chamber. Below the latter and across the lower edge of 75 the wall 13 extends a raised bottom 16 whose edges are engaged in a crimp 17 in the outer wall 11, thereby forming a non-conducting chamber 18 below the compartment 12. The lower edge of the body 11 is adapted to 80 fit within the guides 5 and by them be centered upon the bottom 4, whereby the body or outer wall of the nest will be spaced all around from the body 1 of the shell. By preference the body 11 is of somewhat less 85 height than the shell, as best seen in Fig. 4.

The cover for this device comprises a top plate 20 from which depends an annular skirt 21 of a diameter to stand about midway between the body 1 of the shell and the 90 outer wall 11 of the nest, and of a depth to extend to a point about opposite said crimp 17. In addition, the cover also comprises a second plate 22 fitting within said skirt and forming a non-conducting chamber 23 between it and the top plate 20; a smaller or supplemental skirt 24 depending from the plate 22, and of about the same diameter as the outer wall 11 of the nest; and a series of supplemental plates 25 across and within 100 this supplemental skirt and forming a plurality of non-conducting chambers 26 between them and below the plate 22. Thus it will be seen that by placing the cover in position as shown in Fig. 4, a plurality of 105 non-conducting chambers 26 and 23 will be superimposed above the nest, the latter will 110

2

be surrounded by a plurality of non-conducting chambers consisting first of that numbered 14 in its own body, and next by those inside and outside of the skirt of the cover, 5 and the nest will also have a non-conducting chamber 18 beneath it. By preference these chambers are empty so as to constitute air spaces, although it is contemplated that they 10 may be wholly or partially filled with any suitable material which is a non-conductor of heat, for which purpose I have called them "non-conducting chambers" as their function is to prevent the escape to the outside 15 of the heat contained within the nest proper as represented by the compartment 12. In operation, meats, fowls, vegetables, cereals and the like are put into the kettle, brought to the boiling point on a stove, range, or similar source of heat, kept at that temperature 20 from one to ten minutes according to the article being cooked, and then quickly removed within the same receptacle which is placed in the nest of this improved fireless cooker and is allowed to remain there for 25 several hours until the process of cooking is completed. This latter results from the fact that the temperature of the material of the kettle and its contents has been raised sufficiently high to cook the latter, and by 30 the use of a fireless cooker with non-conducting chambers surrounding its nest the temperature is retained so that the cooking process really continues after the kettle is removed from the stove.

35 In Figs. 5 and 6 I have shown amplifications of this idea in which several independent cookers are contained within a surrounding casing 30 which may be shaped to cause the best results. Whether there shall be 40 packing 31 within the casing and outside and around the shells 1 is an immaterial matter, as also whether the casing shall have an independent cover or not.

What is claimed as new is:

45 1. A fireless cooker comprising a shell, a nest therein, and a cover having a skirt and a plurality of separated plates rigidly held therein and forming a plurality of non-conducting chambers superimposed above the 50 nest.

55 2. A fireless cooker comprising a shell, a nest therein, a plurality of non-conducting chambers surrounding the nest between it and the shell, a cover having a skirt, and a plurality 60 of separated plates rigidly held therein and forming a plurality of superimposed non-conducting chambers in the cover above the nest.

65 3. A fireless cooker comprising a shell, a nest centrally disposed therein and with its bottom raised above that of the shell to form a non-conducting chamber between them, a plurality of such chambers surrounding the nest between it and the shell, a cover having a skirt, and a plurality of separated plates

rigidly held therein and forming a plurality of non-conducting chambers in the cover superimposed above the shell.

4. A fireless cooker comprising a shell having an open top and a closed bottom, and peripheral guides on the latter directed toward its center; a nest consisting of a cylindrical body fitting between said guides, a raised bottom forming a non-conducting chamber below it, and a non-conducting chamber surrounding its central opening; and a cover consisting of a skirt adapted to stand midway between said shell and the outer wall of the nest, and a series of plates within the skirt and forming non-conducting chambers superimposed above the nest. 70 75

5. A fireless cooker comprising a shell having an open top and a closed bottom, and peripheral guides on the latter directed towards its center; a nest consisting of a cylindrical body fitting within the guides, a raised bottom secured across the body and forming a non-conducting chamber beneath, an inner wall secured upon said bottom and forming a non-conducting chamber surrounding the 80 central pot-compartment, and an annular cover rigidly connecting said inner wall and the body; and a cover for the whole including a series of non-conducting chambers adapted to rest upon said annular cover and to extend 85 over and close the pot-compartment. 90

6. A fireless cooker comprising a shell; a nest consisting of a body centrally disposed therein and crimped, a false bottom held in the crimp, and a non-conducting chamber 100 supported on said bottom; and a cover for the nest having a skirt adapted to stand between said shell and the outer wall of the nest, and a plurality of non-conducting chambers of which some stand above the 105 nest and its chamber and at least one is larger and extends over the space between said skirt and the outer wall of the nest. 110

7. A fireless cooker comprising a shell having an open top and a closed bottom, and peripheral guides on the latter directed towards its center; a nest consisting of a body fitting between said guides and crimped, a false bottom held in the crimp and forming a non-conducting chamber below it, and a non-conducting chamber surrounding its central opening and having a closed top; and a cover having a skirt adapted to stand between said shell and the outer wall of the nest, and a plurality of non-conducting chambers of 115 which some stand above the nest and the closed top of its chamber and the remainder of larger diameter stand above said first-mentioned chamber and extends out to said skirt. 120 125

8. A fireless cooker comprising a shell having an open top; a nest of less height than the shell and consisting of an outer wall parallel with but spaced from said shell, an inner concentric wall spaced from the outer wall to 130

form a non-conducting chamber surrounding the pot-compartment inclosed by said inner wall, an annular cover closing the top of said chamber, and a bottom closing both the chamber and compartment; and a cover consisting of a top plate, a skirt adapted to stand between said outer wall and shell, a plate within the skirt above the top plate, a supplemental skirt depending from said top plate, and supplemental plates within the

supplemental skirt, all said plates being spaced to form a plurality of non-conducting chambers.

In testimony whereof I sign my name in the presence of two subscribing witnesses, 15 this 29th day of April, 1907.

HARRY H. CREA.
